CLAIM

The ornamental design for a frame member for ride-on power trowel, as shown and described.

DESCRIPTION

FIG. 1 is an isometric view of the front, right side, and top of a frame member for ride-on power trowel;

FIG. 2 is a front view of a frame member for ride-on power trowel in place on a ride-on power trowel;

FIG. 3 is a right side view of a frame member for ride-on power trowel in place on a ride-on power trowel;

FIG. 4 is a back view of a frame member for ride-on power trowel in place on a ride-on power trowel;

FIG. 5 is a top view of a frame member for ride-on power trowel in place on a ride-on power trowel;

FIG. 6 is a left side view of a frame member for ride-on power trowel in place on a ride-on power trowel;

FIG. 7 is a bottom view of a frame member for ride-on power trowel in place on a ride-on power trowel;

FIG. 8 is an isometric view of the front, right side, and top of a frame member for ride-on power trowel in place on a ride-on power trowel;

FIG. 9 is a front view of a frame member for ride-on power trowel in place on a ride-on power trowel in a second configuration; and,

FIG. 10 is an isometric view of the back, top, and right side of a frame member for ride-on power trowel in place on a ride-on power trowel.

The broken line showing of the ride-on power trowel is included for the purpose of illustrating environmental structure and forms no part of the claimed design.
